UNITED STATES PATENT OFFICE

ARTHUR T. PRESCOTT, OF EAST ORANGE, NEW JERSEY, ASSIGNOR TO J. EDWARD OGDEN COMPANY, INC., OF EAST ORANGE, NEW JERSEY, A CORPORATION OF NEW JERSEY

DOOR CONSTRUCTION AND OPERATING MECHANISM THEREFOR

Application filed March 20, 1930. Serial No. 437,292.

This invention relates to doors and particularly to door constructions and door operating mechanisms for pier sheds and like structures.

5 In order to make full use of the space in a pier shed or like structure, the cargo to be stored must be handled several times. For instance, the cargo is first deposited on the floor of the pier shed and is then piled up or 10 stacked. This duplication of handling consumes time and adds to the expense of storing cargoes.

15 This invention has for its salient object to provide door structures and associated parts so constructed and arranged as to facilitate the unloading and stacking of cargoes in pier sheds or like building constructions.

20 Another object of the invention is to provide door closures and operating mechanisms therefor, so constructed and arranged and so operated that the doors when opened can be moved bodily away from the door opening to permit the direct stacking or piling of the cargo to a maximum height in the pier shed 25 without additional handling.

Further objects of the invention will appear from the following specification taken in connection with the drawings, which form a part of this application, and in which

30 Fig. 1 is a vertical, sectional elevation through a pier shed illustrating door closures and operating mechanism therefor constructed in accordance with the invention;

35 Fig. 2 is a top plan view, partly in section, of a portion of the door structure and operating mechanism illustrated in Fig. 1;

40 Fig. 3 is a top plan view of the hatch cover or roof section disposed above the door opening and movable bodily away from the door opening;

Fig. 4 is an enlarged sectional elevation taken substantially on line 4—4 of Fig. 1;

45 Figs. 5 and 6 are enlarged sectional elevations taken substantially on lines 5—5 and 6—6 of Fig. 1;

Fig. 7 is an enlarged sectional elevation taken substantially on line 7—7 of Fig. 2, parts being omitted for the sake of clearness; and

50 Fig. 8 is an enlarged sectional elevation

taken substantially on line 8—8 of Fig. 2, parts being omitted for the sake of clearness.

The invention briefly described consists of the combination of a building structure, such as a pier shed, having a door opening, a door closure therefor, and operating mechanism for opening the door adapted to move the door to open position and thereafter to move the door inwardly away from the door opening or jamb. The invention preferably includes a carriage or frame into which the door is moved when the door is operated to open position and means for moving the frame and door inwardly and to a slight degree upwardly away from the door opening or door jamb. The invention further provides a movable hatch cover or roof section and means for moving the hatch cover or roof section with the door frame and door inwardly away from the door jamb and upwardly whereby the cargo can be swung into the pier shed through the opening in the roof, thus facilitating the piling or stacking of the cargo to the full maximum height in the pier shed without requiring more than one handling operation.

Further details of the invention will appear from the following description.

The pier shed or building structure in which the door closure and operating mechanism is embodied may be constructed in any desired manner and it is common in such structures to provide door openings and doors at both longitudinal sides of the pier, as shown at A and B in Fig. 1. Portions of the side walls of the pier shed are shown at 10 and 11 in Figs. 5 and 6, the door jambs which bound the door openings being shown at 12 and 13. Angular frame structures 15 and 16 coact with the inner edges of the jambs 12 and 13 to form vertical guideways for receiving the door or door sections.

In the form of the invention illustrated, the door comprises a pair of door sections 20 and 21 which are movable vertically and laterally to open position. The door sections may be hung or supported in any desired manner, and in the embodiment of the invention shown, the upper sections are hung on

links 22. The lower section 20 is first moved to a position side by side with the upper section and the two sections are then moved as a unit upwardly and inwardly. This construction is old and common in the art and need not be described in detail.

After the lower door section has been moved to a position by the side of the upper section, the two sections are moved bodily vertically and inwardly into a frame or carriage F. The frame F has a transverse front frame member 25 which forms the door header and comprises rearwardly extending frame members 26 which are connected by the member 25 and by cross frame members 27 and suitable bracing members 28 and 29. At its rear end the frame has a frame member 30 provided at its lower edge with a shelf 31 adapted to engage and support the rear edges of the door sections 20 and 21. The links 22 are pivoted at their upper ends, as shown at 32, to the frame F, and at their lower ends are pivoted, as shown at 33, to the lateral edges of the frame 34 which carries the door section 21 and is adapted to receive the lower door section 20.

Operating Mechanism for Raising Door Sections into Carriage or Frame F

The operating mechanism for moving the door sections into the frame F is carried by the frame and is mounted at the rear end of the frame, as shown particularly in Figs. 1, 2 and 4. This mechanism consists of a motor M having a gear 40 mounted on the motor shaft and meshing with a gear 41 mounted on a jack shaft 42. The shaft 42 has secured thereto a worm gear 43 which meshes with a gear 44 carried by a shaft 45 which extends transversely across the rear end of the frame or carriage F. The shaft 45 has secured to each end thereof, a drum 46 to which is secured one end of a cable 47. The cables 47 pass around sheaves 48 carried by spindles 49 and are connected at their ends, as shown at 50, to the lower lateral edge portions of the door sections 20.

When the operator desires to open the door, the motor circuit for the motor M will be closed by a push button or other suitable device located adjacent the door opening and the motor will, in the manner above described, cause the shaft 45 to rotate, thus winding the cables 47 on the drum 46 and lifting the lower section 20 to a position adjacent the upper section and thereafter swinging the two sections as a unit inwardly on the links 22 to a position in which the two sections will be supported in the frame or carriage F.

After the door sections have been moved into the frame or carriage F, the carriage and the hatch cover or roof section above the carriage are moved inwardly and to a slight extent upwardly, the door sections being, of course, moved with the carriage.

The frame F is supported on a pair of tracks or rails 55 and 56. Rollers 57 and 58 engage the rails at the rear end of the frame and the front end of the frame is supported on the rails by wheels or rollers 59.

Mechanism for moving carriage F, door and hatch cover inwardly away from door opening

The pier shed roof is provided with a movable section or hatch cover C normally supported on side rails or hatch coamings 60. The rear edge of the cover C has brackets 61 secured thereto and extending rearwardly therefrom, rollers 62 being carried by the brackets at the rear ends thereof. The rollers 62 rest on rails 63 which are preferably beveled at their lower ends, as shown at 64, the rails being carried by the roof of the pier shed.

The cover C is supported at its front end on the header 25 carried by the frame or carriage F. The front and rear ends of the cover are provided with flanges 65 and 65', the flange 65 being adapted to coact with a vertical flange 66, and the front flange 65' having secured thereto a strip 67 which is spaced from the flange 65' and forms a groove for receiving an upwardly extending strip 68 carried by the header 25. The strips 67 and 68 act as weather strips to close the opening between the hatch cover and header.

The rear edge of the cover C is supported by the rollers 62 on the tracks 63. The front edge of the cover is supported by links 70 which at their upper ends engage brackets 71 secured to the inner front edge portion of the cover and are secured at their lower ends to arms 72 carried by a shaft 73 which is supported in suitable brackets carried by the header 25. The shaft 73 has connected at the ends thereof, arms 75 to which are secured cables 76.

The cables or chains 76 pass upwardly around a sheave 80 mounted on a shaft 97 carried by fixed supports 81 and downwardly around sheaves 82, and counterweights W are connected to the lower ends of the cables. The cables or chains are operated by the sheaves 82 and are preferably of chain type, the sheaves 82 coacting with the cables to move the cables as the sheaves are operating.

The cables 76 may be operated in any desired manner and in the form of the invention shown there is illustrated a hand operated chain 85 which is mounted on a sheave 86 connected by a gear connection 87, 88 to drive a shaft 89, which in turn is connected by a gear connection 90, 91 to drive the shaft 92 on which the sheaves 82 are mounted. Sheaves 82 are provided at each side edge of the door. The sheave 82 at the right in Fig. 2 is driven by the gear connection just described. This sheave by

the chain or cable 76 drives the sheave 80. The shaft 97 is rotated by the rotation of sheave 80 and extends across the roof structure and has secured to its other end a sheave 80'. The sheave 80' is connected by chain 76' to drive the sheave 82 at the left hand edge of the door opening, viewing Fig. 2.

It will be obvious that when the hand chain 85 is operated, the gearing operated 10 by the hand chain will cause the sheaves 82 to be rotated, thus moving the cables 76 in the direction of the arrows shown in Fig. 7 and causing the arms 75 to move in an anti-clockwise direction. The movement of 15 the arms 75 will rotate the shaft 73 and the arms 72 carried thereby, thus causing the links 70 to lift the front edge of the hatch cover C to the position shown in Fig. 7. Further movement of the arms 75 is prevented 20 by a stop 100. As the hand chain 85 is further operated, the movement of the cable 76 in the direction of the arrow in Fig. 7 will cause the carriage or frame F and the hatch cover C to move upwardly and rearwardly to the position shown at the right 25 in Fig. 1. During this movement the hatch cover C will be free from the upper edge of the coaming and the front flange or edge 65 of the cover will also be slightly elevated, 30 thus eliminating friction. When the frame or carriage, door sections carried thereby, and hatch cover have been moved upwardly and rearwardly, the opening through which the cargo can be deposited in the pier shed 35 will be materially increased, thus permitting the stacking of the cargo by one operation instead of by a plurality of operations.

Résumé of operation of door opening mechanism

In order to cause the doors to open, the motor M is energized by the operation of a push button or any other desired form of switch, whereupon the door sections will be 45 raised and swung inwardly to a position in which they are supported in the frame or carriage F. If it is then desired to unload a cargo into the pier shed, the hand chain 85 will be operated, causing the cables 76 to lift 50 the hatch cover at the front end thereof and thereafter to move the carriage or frame F, door sections carried thereby, and cover upwardly and rearwardly to the position shown 55 at the right in Fig. 1.

In order to close the doors and the parts associated therewith, the hand chain 85 is operated in the reverse direction and the movement of the frame and hatch cover 60 from the position shown at the right in Fig. 1 to closed position is facilitated by the action of gravity since the tracks for supporting the frame and the rails for supporting the cover are inclined. The doors can then be 65 closed by the reverse operation of the mo-

tor M, causing the cables 47 to unwind from the drums 46.

Although one specific embodiment of the invention has been particularly shown and described, it will be understood that the invention is capable of modification and that changes in the construction and in the arrangement of the various cooperating parts may be made without departing from the spirit or scope of the invention, as expressed 75 in the following claims.

What I claim is:

1. In combination, a structure having a door opening, a hatch cover above said opening, hatch coamings for supporting said cover, a door for closing said door opening, means for opening said door, and means for successively raising the cover free of said coamings and moving the door and cover rearwardly of the door opening.

2. In combination, a structure having a door opening, a hatch cover above said opening, hatch coamings for supporting said cover, a door for closing said door opening, means for opening said door, and means for successively raising the cover free of said coamings and moving the door and cover upwardly and rearwardly of the door opening.

3. In combination, a structure having a door opening, a door for closing the opening, rails, a carriage mounted on said rails, means for moving the door upwardly and rearwardly onto said carriage, means for moving the carriage and door rearwardly on said rails, a movable hatch cover above the carriage, and operative connections between the carriage and hatch cover whereby the movement of the carriage will cause the cover to move rearwardly.

4. In combination, a structure having a door opening, a door for closing said opening, a carriage, means for opening said door and moving the door to a position on said carriage, a hatch cover above the carriage, and means for moving the carriage and cover upwardly and rearwardly.

ARTHUR T. PRESCOTT.
